PERCUSSION DRILL

Carl Hömen, Hamburg, Germany

Application June 21, 1939, Serial No. 280,230
In Germany April 24, 1939

2 Claims. (Cl. 255—41)

This invention relates to compound percussion drills, that is to say, drills which can be arranged to operate either with a percussion or with a rotary action, or with a combined rotary and percussion action.

One object of the invention is to improve the construction of such drills so as to give them a compact form.

Another object of the invention is to simplify the construction of such drills to produce a cheaper and more robust instrument.

A further object of the invention is to provide a compound drill which can easily and simply be switched over from the percussion action to the rotary action and vice versa.

These and other objects will best be understood from the following description, in which one form of drill in accordance with the invention is described by way of example and with reference to the accompanying drawing, in which—

Figure 1 is a longitudinal section through the drill.

Figure 2 is a view of the clutch immediately after a blow has been delivered;

Figure 3 is a similar view just before a blow is delivered; and

Figure 4 is a plan of the brake mechanism used to convert the tool into a pure impact drill.

The drill shown in the example is driven by an electric motor. All the driving members are housed in the casing consisting of two parts 1 and 2, the upper part 1 carrying the handle 3 by which the drill is held. In the upper part 1 of the casing magnetic poles 4 are arranged, between which a cylindrical armature 5 revolves. The armature 5 is carried on an inner cylindrical casing 6 which is rotatably mounted, by means of ball bearings 7, on the inner casing 2 which projects upwardly into the outer casing 1.

The inner armature casing 6 carries a cover 8 which is secured to the bush 9 which is in turn fixed to the driving shaft 10, which is journaled at its upper end in the top of the upper part 1 of the casing. The driving shaft 10 carries at its lower end a hammer head 11 and the driving member 12 of a dog clutch, this member being slideable and rotatable within the lower casing part 2.

The driven member 13 of the dog clutch, which is driven by the driving member 12, is mounted in the lower casing part 2 and is rigidly connected to the bit holder 14, which passes downwards through the extension 15 rigidly fixed to the casing part 2. The upper end of the bit holder 15 carries an impact head 16 which is

positioned opposite the hammer head 11. The bit holder 14 is urged downwards by means of a spring 17, whilst another spring 18 presses downwards on the driving member 12 of the dog clutch. In order to make it possible to adjust the force of the impacts, an adjusting device 19 is provided in the head of the casing part 1, which enables the compression of the spring 18 to be adjusted, and hence the force of the impacts, by moving the collar 20. The device 19 can be held firmly in any desired position by means of the spring clamp 21.

To avoid the possibility of the bit 22 being flung out of the holder 14 as a result of an impact from the drill occurring before the tool has been correctly positioned against the workpiece, an occurrence which might lead to injury of the operator, a spring safety catch 23 is provided on the holder 14, which engages a collar 24 on the bit 22, when the tool is in operation. The spring action of this catch also prevents the bit working loose in the holder when the tool is in operation. A depth indicating device 25 is arranged on the lower part of the drill, which can be moved up and down and secured in any position. It may enclose the catch 23, so that it will not interfere with it. This enables a workman to determine before hand the depth of the hole being drilled and prevents this depth being exceeded. This is particularly useful when dowels or pegs are to be subsequently inserted into the holes and are of a fixed size.

In order to increase the number of blows delivered in unit time, a brake is provided to impede the rotation of the bit-holder and comprises two wedge shaped brake blocks 26 which engage corresponding conical surfaces on the brake rim 13. The brake blocks 26 are pressed against the brake rim 13 by means of springs 27 which are actuated by intermediate members 28 which in turn are pressed inwards by means of the conical surface 29 on the sleeve 32. By applying the brake to a sufficient extent the rotation of the bit can be entirely stopped so that the tool works purely as a percussion drill.

It is also possible to make the tool function purely as a rotary drill, even when turning in the same direction as when operating as a combined rotary and impact drill. This is done by means of the sliding pins 30, which are operated so as to enter the groove in the driving member 12 and thus prevents the dog clutch from disengaging, so that no blows can be delivered. The pins 30 are spring biased towards their inoperative positions and are brought into operation by

means of the conical surface 31 on the sleeve 32. When this sleeve is in its normal position both the pins 30 and the brake blocks 26 are out of action. When the sleeve is moved upwards (towards the handle) the pins 30 are brought into operation, and when it is pushed downwards the brake is brought into operation. The fact that a single control member performed both these functions is a great advantage, as it automatically ensures that the two devices cannot be brought into operation simultaneously, a matter of importance as the tools are usually used by relatively unskilled workmen. This arrangement also prevents damage to the essential parts of the machine by incorrect use.

In order to avoid having to replace the whole of both clutch members when the dogs of the clutch become worn or damaged, the dogs are pressed on to their respective members 12 and 13 and secured by pins or dowels as shown in Figure 1.

The operation of the drill is as follows:

When the drill is switched on, the armature 5 rotates, driving the shaft 10 and clutch member 12 with it. As the bit 22 initially encounters no resistance, it is rotated through the clutch. If the tool is now brought against a piece of brick-work, the frictional resistance may still remain fairly small to start with if the material is soft and in this case the drill continues to operate as a rotary one. If the bit then encounters hard material, the corresponding frictional resistance to rotation will increase. The bit holder 14 is then prevented from turning, so that the clutch member 13 is held fast. This causes the clutch member 12 to lift against the force of the spring 18 and to disengage. As the clutch re-engages the hammer 11 delivers a blow on the head 16, so that the projecting piece of material at the bottom of the hole, which was preventing rotation of the bit, is broken away. The bit can then continue to turn until it encounters the next obstacle in the hole.

If a hole is to be drilled in soft material, the sleeve 32 can be moved upwards (as viewed in Figure 1) so that the clutch is prevented from disengaging by means of the pins 30, so that no blows can be delivered.

If, on the other hand, a hole is to be drilled in a hard material the brake blocks 26 are urged against the brake rim by means of the sleeve 32, which is screwed downwards as viewed in Figure 1, so that rotation of the bit 22 is prevented and the clutch is continually engaged and disengaged so that continual blows are delivered. The operator works with one hand on the handle 3 and

the other on the sleeve 32, so that the drill can very easily be adjusted during operation to give either impacts only, or to rotate only, or to give a combination of the two.

It will be apparent to those skilled in the art that various modifications of the construction described are possible without departing from the spirit of my invention, and I do not intend to be limited except as is set out in the following claims.

I claim:

1. A compound rotary and percussion drill, comprising a hollow cylindrical armature, a driving shaft connected to said armature, a bit-holder co-axial with said driving shaft, an overrunning clutch comprising a driven member and a driving member, said driven member being connected to said bit holder, said driving member being mounted on said driving shaft, a spring compressed by said driving member, upon relative angular movement of said driving and driven members, said clutch being disengaged against the action of said spring upon relative angular movement between said driving shaft and said bit holder, a hammer operative upon a re-engagement of said clutch and when said spring is extended again to deliver a blow to said bit holder, locking means for locking said clutch against disengagement, braking means for locking said bit holder against rotation, and control means for operating said locking means and said braking means separately and to prevent them from operating together.

2. A compound rotary and percussion drill, comprising a driving shaft, a bit holder co-axial with said driving shaft, a clutch connecting said driving shaft with said bit holder and including a spring; said clutch being disengaged against the action of said spring upon relative angular movement between said driving shaft and said bit holder, means operable upon a re-engagement of said clutch to deliver a blow to said bit holder, locking means for locking said clutch against disengagement, braking means for locking said bit holder against rotation, and control means for operating said locking means and said braking means to operate said locking means and said braking means separately and to prevent them from operating together, and comprising an axially movable sleeve having two inner conical surfaces, one of said surfaces being adapted to engage means operating said locking means, the other one of said surfaces being adapted to engage means operating said braking means.

CARL HÖMEN.
